UNITED STATES PATENT OFFICE.

RALPH EUGENE PAGE, OF BINGHAMTON, NEW YORK, ASSIGNOR TO THE TABULATING MACHINE COMPANY, A CORPORATION OF NEW JERSEY.

SINGLE-COLUMN SELECTOR FOR CARD-SORTING MACHINES.

1,426,499.

Specification of Letters Patent. Patented Aug. 22, 1922.

Application filed June 11, 1921, Serial No. 476,961. Renewed January 16, 1922. Serial No. 529,448.

To all whom it may concern:

Be it known that I, RALPH E. PAGE, a citizen of the United States of America, residing at Binghamton, in the county of 5 Broome and State of New York, have invented certain new and useful Improvements in Single-Column Selectors for Card-Sorting Machines, of which the following is a full, clear, and exact description.

10 In many branches of industry at the present day the use of tabulating machines has become very general and they are coming to be regarded as indispensable. In these machines cards are used which are first 15 punched or perforated at given points in one or more columns to indicate dates, classes or other distinctive features, and in other columns, amounts or other data, the aggregate or totals of which it may be desired to 20 compute. In conjunction with the tabulating machine proper there is always employed a card-sorting machine which is a piece of apparatus into or through which a number of cards of different kinds or classes 25 are passed, and which operates to sort out from the whole lot all of the cards of a certain definite kind or class, without disturbing the sequence of the rejected or unsorted cards.

30 Tabulator cards have always a certain number of vertical columns of spaces to the number necessary for punching perforations corresponding to the digits and such other arbitrary data as may be required, and certain 35 of these columns are set aside for the perforations which indicate the particular kind or class to which such card belongs. These holes, known as the index holes, are successively brought in the card-sorter into 40 operative or control position under contact brushes, and set by means of the record which they contain the mechanism which is instrumental in controlling their delivery into the appropriate compartment or receptacle, while those cards which it is not desired 45 to sort out, have no effect upon the sorting mechanism, but simply pass through and into a general delivery receptacle.

Card sorting machines are equipped with 50 selectors which act upon the whole or any part of a single indicating column at a time, and these attachments are provided with means which may be set or adjusted to act

in response to any definite perforation in the column and thus sort out only those 55 cards which have such perforations. Such devices are known as single column selectors, and to this class of devices belongs the apparatus which I have devised, and upon which is based the present application for 60 Letters Patent. This apparatus is an improvement upon those which preceded it in being more simple in construction and operation, while at the same time it is capable of performing all of the operations of single 65 column selectors either for straight sorting, or, in other words, picking out cards with index holes punched in any part of a column or for split sorting, by which is meant selecting those cards only which have holes 70 punched in one part of a column.

The improved device is shown in the accompanying drawings in which:

Figure 1 is a side view chiefly of the exterior of the device which constitutes an 75 attachment to a card sorter.

Fig. 2 is an end view of the same.

Fig. 3 is a sectional view on the line 3—3 of Fig. 1.

Fig. 4 is a view in elevation looking to 80 the right from the line 4—4 of Fig. 2.

Fig. 5 is a detail sectional view, and

Fig. 6 is a wiring diagram, illustrating the mode of operation of the device.

The attachment is provided with a support having legs 1, and is adapted to be set upon the frame of a card-sorting machine in such position and relation thereto that it may be driven thereby through a gear wheel 2, at such rate that its shaft 3 makes one 90 complete revolution or cycle for each card that passes through the sorter. To the shaft 3 at its inner end is secured an insulating bushing 4, and to this bushing is clamped by a screw 5 a brush-holder 6, carrying a 95 brush 7.

Rigidly fixed to the brush-holder 6 is a plate 8 with a central projection 9 upon which latter bears a spring 10 which thus maintains electrical contact therewith, the other end of said spring 10 being secured to a terminal post 11 set in a molded insulating distributor ring 12. By this means the circuit is completed from the post 11 to the brush 7.

The insulating distributor ring 12 is prop-

erly secured to the frame or support of the instrument and molded into it is a metal distributer ring 14 having a single projection extending therefrom through the insulating ring 12 to form a terminal binding post 13. There are also set or molded into the ring 12 eleven contact blocks 15, spaced 1/14 of the circle apart and insulated from each other.

- 10 To the metal distributer ring 14 there are secured contact springs 16 spaced 1/14 of the circle apart, which springs lie over the contact blocks 15 but are normally held by their resilience out of contact therewith.
- 15 In conjunction with these springs there are a series of contact plugs 17 constructed as shown in Fig. 5, and properly set in a circular ring support 18 which may be of insulating material, or if not, insulated from 20 said plugs. There is a plug 17 over each spring 16, and they are constructed or arranged in any well known manner to remain in either their "in" or "out" positions in the ring 18 to which they may be adjusted. When a plug is pushed in, it presses 25 its underlying spring 16 into contact with the contact block 15 immediately beneath it, and thus completes the circuit from such block to the terminal post 13. This part 30 of the circuit is manifestly interrupted when the plug is pulled out.

The operative parts of the device are enclosed by suitable plates 19 which are held by proper screws and, as shown in Fig. 1, 35 numbers are stamped on the casing close to the index buttons or plugs 17, which correspond with the horizontal rows of numbers on a card, or to the numbers which may be punched out from the card.

- 40 The brush 7 is so timed in its movement that is makes contact with a contact block 15 at the moment that the contact brush 21, Fig. 6, in the sorting machine makes contact through one of the holes in the card 45 passing through the sorter, with the roller or metal plate 22.

Referring now to Fig. 6: The index buttons or plugs 17 are here represented as switch levers which electrically connect the 50 ring 14 with the blocks 15, and the brush 7 is represented as a rotor which in its movement makes contact successively with the blocks 15. The cards to be sorted are passed successively between the contact brush 21 55 and the plate 22, and when a perforation in a card comes under the brush the current from a suitable source as 23, flows and energizes the sorting magnet 24, which by means of a suitable device delivers the card 60 into its appropriate compartment or receptacle.

The control contacts 25 are not new in connection with a sorting machine, and are intended to complete the circuit at this 65 point after the bottom edge of the card is

just below the contact brush and before the brush makes contact through a number 9 hole. These contacts 25 are also intended to open this circuit after the brush has passed an X hole and before the top edge of 70 the card is at the contact brush. The purpose of this is to give ample time and opportunity for the operation of the machine when the brush is passing over the space between the cards. It will be borne in mind 75 that in sorting cards the contact brush 21 makes contact first through the 9 hole in the card and the others in the reverse order of their numerical values, becomes the cards are fed into the machine right side up. Any 80 card punched with a hole in the extreme top or R position will be delivered into the R or reject box.

To use this device for straight sorting all of the index buttons will be pushed in 85 so that cards will be sorted solely under the control of the brush and contact member 22 according to the position of a hole in any part of a vertical column. To split the column, as it is called, at any desired point, 90 as between the 6 and 7 positions in a vertical column, and to reject all cards having index point perforations of 7, 8 and 9, all the index buttons except those marked 7, 8 and 9 will be pushed in, in which event 95 all cards that have holes punched in them in the 7, 8 or 9 position will be bunched and rejected while all others will be sorted into their appropriate boxes, under control of the brush 21 and contact 22. It 100 may also be desired to split the column and to select only in accordance with one or a plurality of the index points of the passing cards. Applied to the previous illustration either one or more of the buttons 1, 2, 3, 105 4, 5 or 6 could be pulled out in which case the sort would only be effective on the positions corresponding to the button or buttons which were in "in" position, etc. Further the device may be used for selecting such 110 cards which have only a certain hole. If cards which have, say, the 5 hole, punched are to be selected from a pack, the index plug No. 5 alone is pushed in and all others would be left out. In this case all cards 115 except those containing a 5 hole would go to the reject box.

To select more than one position, say, 2 and 4, the 2 and 4 index buttons are pushed in and the others are left out. In this case 120 if cards pass through the machine having either a 2 or a 4 hole punched therein but not both, such cards will be sorted into their respective boxes and all others will be rejected. If, however, there are cards in the 125 pack having both the 2 and 4 hole therein, it would be sorted into the No. 4 box and the cards from this box would have to be sorted again, with only the 2 button pushed in in order to classify them. The 130

same method would be followed in split sorting with cards in the bunch having two holes in the same card column in the selected split section and with two buttons 5 pushed in.

The results which may be accomplished will readily be understood from the diagram Fig. 6. Here it is shown that the sorting circuit is under a plural control; 1st, that 10 directly controlled by the index points of the card which is secured by means of the sorting brush and contact 21-22. Second, there is a supplementary control which is secured by rotating brush 7 and the button 15 controlled switches 17. In order that a card go to a particular box it is necessary that the sorting circuit be concurrently established through all controlling points.

From the above explanation it will be 20 understood how the device is to be used under all other conditions met with in practice in the use of these machines. The apparatus has been found to be a very efficient 25 and highly useful means of utilizing to the best advantage the possibilities of the cards and of the apparatus heretofore in use, and to greatly extend the field of usefulness of the sorting machine by simplifying many 30 operations where it is desired to distinguish and select out cards of a certain class or character.

The device as shown and described above, is designed and adapted for use with a card sorting machine, but the nature of the 35 results secured by its use renders it applicable to other uses and purposes. I desire therefore to cover not only the device in combination with a card sorter, but as a useful apparatus of itself.

40 Having now described my invention, what I claim is:

1. In a single column selector for card sorting machines, the combination with two terminals adapted for connection with the 45 sorting mechanism, of a movable brush connected with one terminal and adapted to complete one cycle of movement while a card is passing through the sorting machine, a series of evenly spaced contact blocks over 50 which the brush passes, an overlying series of contacts electrically connected with the other terminal normally out of engagement with said blocks, and means for connecting up any or all of said contacts and blocks 55 whereby circuit paths between the said terminals will be completed through the said connected contacts.

2. In a single column selector for card sorting machines, the combination with two 60 terminals adapted for connection with the sorting mechanism of a rotary brush connected with one terminal and adapted to make one complete rotation while a card is passing through the sorting machine, a series of evenly spaced contact blocks over 65

which the brush rotates, an overlying series of contact springs electrically connected with the other terminal but normally out of engagement with the contact blocks and means for bringing and maintaining any or all of 70 said contact springs in engagement with the contact blocks whereby circuit paths between the said terminals will be completed through the engaging contacts.

3. The combination with the shaft adapted to make one revolution while a card is passing through a sorting machine, a brush carried by said shaft, a circular series of evenly spaced contact blocks over which the brush travels, a metal ring with spring contacts thereon which overlie, but do not engage, said contact blocks, a series of index plugs or buttons for forcing said contact springs into engagement with the blocks, and circuit connections from the brush and 80 from said contact springs adapted for connection with the sorting mechanism of a card sorter.

4. The combination with an insulating support, of a distributor metal ring, and a plurality of metal contacts set in the said support, a series of spring contacts overlying said contacts and normally out of engagement therewith, said spring contacts being secured to the distributor ring, a brush movable over the said contacts, means such as movable plugs for forcing any one or all of said springs into engagement with their underlying contacts and circuit terminals connected respectively with the brush and 100 the distributor ring.

5. In a single column selector for a sorting machine, in combination, means for controlling a sorting circuit, comprising means for successively closing a portion of said circuit every time another portion of said circuit is established under the control of the index points of a record card, and means independent of the index point perforations in the cards for selectively closing said circuit at one or more other points in correspondence with the index point positions to selectively predetermine upon which index point or points the sort is to be effective. 105

6. A controlling means for a circuit controlled at one point by the index point perforations of record cards, comprising a supplementary circuit closer adapted to successively close the controlling circuit at a second point as each index point perforation 110 is reached, and a plurality of switches for selectively opening or closing the controlling circuit at one or more of the successive positions at which the circuit is established by the supplementary circuit closer. 115

7. In a single column selector for a sorting machine, in combination, means for controlling the sort of cards passing through a sorting comprising means for selectively controlling the sorting of said cards in ac- 120 125 130

cordance with any one, or any plurality of, or all of the index points of any given single column of passing record cards.

8. In a single column selector for a sorting machine, comprising an attachment adapted to permit split sorting of cards having split columns with index points in each split portion of said column, and having in combination therewith means for selectively controlling the sort in accordance with any one index point in any split portion.

9. In a single column selector for a sorting machine, in combination, a sorting circuit, means for controlling the same, a plurality of circuit closers selectively operable to close or open one or a plurality of circuits from said sorting circuit to one or a plurality of points, a movable member for successively closing a circuit to said points as 20 the successive index points of passing record

cards pass their circuit controller, said circuit closer and said movable member being adapted to cooperate to conjointly control the sorting circuit and to predetermine upon which index points the sort is to be effective.

10. In a single column selector for a sorting machine, in combination, means for controlling a sorting circuit comprising means for successively closing a portion of said circuit as the successive index points of a record car pass under the sorting brush and means for selectively closing said circuit at one or more other points to selectively control the establishment of said circuit by the first mentioned means to predetermine upon which index points the sort is to be effective.

In testimony whereof I hereto affix my signature.

RALPH EUGENE PAGE.
